BUILDING UNIT AND CONSTRUCTION
MADE THEREFROM

Richard R. Colburn, Minneapolis, Minn.

Application December 23, 1940, Serial No. 371,231

14 Claims.

(Cl. 72—16)

This invention relates to building units and building constructions made therefrom and it relates particularly to quickly erected low cost building constructions.

It is one of the objects of this invention to provide a novel and improved skeleton building unit which can be assembled with other similar units to provide a skeleton reenforcement for a building wall to which concrete such as pneumatic concrete can be applied to complete the building wall.

Another object is to provide improvements on the invention disclosed in my application for U. S. patent entitled "Building unit and construction made therefrom," Serial No. 368,578, filed December 5, 1940.

More specifically it is an object of the invention to provide a novel and improved skeleton metal reenforcement forming a building unit to which concrete such as pneumatic concrete can be applied which can be joined to other adjacent units and which includes a metal frame, a pan-shaped metal mesh attached thereto, a backing sheet attached to the frame, and spaced from the main body of the mesh to carry concrete such as pneumatic concrete that may be applied thereto.

Yet another object is to provide a building structure including a reenforced metal frame work, consisting of separate frame units which can be set up and connected together and to which units when so set up, pneumatic concrete can be applied as by a pneumatic gun to produce a monolithic wall.

Still another object is to provide a low cost building structure, which can be erected quickly with a minimum of expense and labor and can be built up into floors, side walls, roof and the like and wherein window frames, door frames etc. can be incorporated.

The objects and advantages of the invention will more fully appear from the following description made in connection with the accompanying drawings, wherein like reference characters refer to the same or similar parts throughout the various views and in which:

Fig. 1 is a view in side elevation of a small one story building embodying my invention, some portions being broken way to show the interior structure, and some portions being shown in vertical section;

Fig. 2 is a vertical section taken substantially on the line 2—2 of Fig. 1 as is indicated by the arrows;

Fig. 3 is a plan view of one of the skeleton building units employed, some parts being broken way

to more clearly illustrate the construction of other parts;

Fig. 4 is a view in side elevation of the skeleton building unit shown in Fig. 3;

Fig. 5 is a view looking toward one edge of the skeleton building unit shown in Fig. 3, Figs. 3, 4 and 5 being in larger scale than Figs. 1 and 2;

Fig. 6 is a horizontal section through a wall of a building built in accordance with the invention showing a door frame structure and external corner;

Fig. 7 is another horizontal section through a wall embodying the invention, showing a window frame structure and an internal corner structure;

Fig. 8 is a vertical section taken through a building incorporating the present invention; and

Fig. 9 is a view in front elevation of portions of a pair of interconnected skeleton building units.

The basic elements of my improved building construction comprise elongated, pan-shaped skeleton building units forming metal reenforcements with coupling means at the edges thereof. These units are first set up and assembled together and are sealed, interconnected, reenforced and bonded together in assembled relation to form monolithic walls, floors and roofs by means of pneumatic concrete or other plastic building material preferably applied to the units in slightly hydrated form through the medium of a spray gun operating under air pressure at the present time, so-called pneumatic concrete is used to coat walls and other surfaces and is applied by spray gun from a dry mixture of cement and sand by blowing the same under high air pressure from the gun, water being added at the nozzle of the gun through a ring valve in just sufficient quantity to hydrate the cement.

Referring to the drawings, there is shown in detail in Figs. 3, 4 and 5 a skeleton building unit A which is typical of the principal unit employed. The unit A includes an elongated rectangular frame 10 formed preferably of angle iron. The frame is preferably formed of a single angle bar forming sides and ends of the frame with lateral flanges of the sides and ends disposed in the same plane and what will be called outwardly projecting flanges lying in planes normal to the lateral flanges and joining the inside edges of the lateral flanges.

In making the frame 10, slits are cut at spaced points through one flange of an angle bar and the other flange of the angle bar is bent at right angles at the points where these slits are cut to form the ends and sides of the frame 10 and the

two ends of the non-slit flange of the angle bar are brought into abutment at one corner of the frame and there welded together. The lateral flanges of the frame which may be designated 10a in counter-distinction to the outwardly projecting flanges which may be designated 10b, are equipped with bolt receiving slots 10c to permit connection of one unit A to adjacent units.

Extending across the frame 10 at the outer side thereof and bearing against the outer edges of the flanges 10b is a rectangular sheet 11. This sheet 11 may be either a stiff building paper such for example, as corrugated asphalt sheet; it may be a sheet of insulating material, such as an insulating board; or it may be a metal sheet. The skeleton building unit A also includes a pan-shaped foraminous reenforcement 12, preferably made of metal lath as shown which encloses the outwardly extending flanges 10b of the frame 10, bridges the sheet 11 and is secured at its edges as by welding or the like to the external sides of the flanges 10b of the frame 10. The main body of the reenforcement or metal lath 12 is spaced outwardly from the sheet 11 and the outer edges of the reenforcement are rounded as shown and the sheet 11 is preferably caught and held in place against the flanges 10b by means of this reenforcement although it will, of course, be understood that the sheet 11 can be otherwise held in position if so desired.

In addition to the skeleton units A which are made preferably of a length corresponding to one story of a building structure, other units B and C are preferably provided, the units B being preferably used below window frames, and the units C being preferably used above window frames and door frames. These units B and C are identical to the units A with the exception that the units A B and C are of shorter length than the units A and the units B and C differ in length. Other units D which are shown in the drawings as being employed as floor units are also provided which correspond to the units A in construction but are of proper length for extension from the units A to form floors of the desired length. There are also provided a number of skeleton building units E, F, G, H and I which are constructed along the lines of the unit A but which are used as gable units and for this reason are of other than rectangular shape. The units E are of triangular shape while the units F, G, H and I are of trapezoid shape, but differ respectively to each other in length. The frames of these units E, F, G, H and I are also made of angle iron preferably to which sheets are applied and to which pan-shaped reinforcements preferably of metal lath are secured in much the same manner as in the case of the units A.

In erecting a building in accordance with the present invention, a foundation or footing 13 as of concrete or cement blocks is first prepared. Then a skeleton metal reenforcement structure is erected on this foundation composed principally of the units A, B, C, D, E, F, G, H, and I. In erecting the skeleton walls for the building, a plurality of the units A, B and C are employed.

For example, two of the units A are first set up vertically, one along side of the other, with the adjacent flanges 10a of the two units overlapping and with the lower flanges 10a of the units resting on the foundation 13. Between the adjacent units, vertical channels 14 are thus formed. Eye bolts 15 are employed for securing together the overlapped flanges 10a of the adjacent units A. These eye bolts fit within the channels 14 and

have screw threaded shanks which project through mating slots 10c of the overlapped flanges 10a. Nuts 16 threaded onto the shanks of the eye bolts 15, bear against the outer overlapped flange 10a of the assembled units. Washers 17 received by the shanks of the eye bolts 15, bear against the inner side of the inner lapped flange 10a of the two units. Extending vertically at the inner side of the two units A opposite the channel 14 is a channel iron 18 through which the shanks of the eye bolts 15 extend and this channel is tightly clamped against the washers 17 by means of nuts 19 threaded onto the inner ends of the shanks of the eye bolts 15. As best shown in Fig. 9, metal reinforcement rods 20 are dropped through the eyes of aligning eye bolts 15 to be received within the channels 14.

If it is desired to have finished interior walls for the building structure, paper-backed metal lath 21 is preferably secured to the channels 18 as by wiring the same thereto by means of wires 22 which pass through the paper-backed metal lath 21 and around the channels 18. The purpose of the washers 17 is to space the channels 18 from the inner side of the inner overlapped flange 10a of adjacent units so that the wires 22 can be worked around the channels 18.

In forming an external corner for the wall as shown in Fig. 6 two of the units A are set at right angles relative to each other and the adjacent flanges 10a are not overlapped but are located closely together as shown with eye bolts 15 to which channels 18 are secured being connected to each of the two adjacent flanges 10a of the adjacent units. V-shaped reinforcing rods 23 are employed at the external corner in conjunction with the eye bolts 15. These V-shaped reinforcing rods 23 have eyes at both ends thereof and at the angle thereof. Reinforcing rods 20 are located at the corner, three rods being used and two of these rods are received within eyes of the eye bolts 15 and within eyes at the ends of the V-shaped reinforcing rods 23, while the third rod 20 is received within the eyes of the V-shaped reinforcing rods 23 at the angles thereof.

When it is desired to produce an internal corner structure for the building as shown in Fig. 7, the adjacent units A are set up as shown at right angles to each other and in place of the eye bolts 15, the adjacent flanges 10a of the two units are connected together and to the channels 18 employed by means of curved rods 24 which have screw-threaded shanks at both ends which run through the slots 10c of the adjacent flanges 10a and carry the nuts 16, washers 17, channels 18, and the nuts 19.

In setting up the skeleton frame work for the building, a door frame 25 within which a door 26 may be mounted may be readily connected to spaced adjacent units A by securing the same as to strips 27 secured as by bolts 28 to the flanges 10a. Of course, when a door frame is incorporated in the wall structure, the proper spacing between adjacent units A is made to take the door frame, the units employed being preferably of such width that the width of a plurality of the units such as two of them will correspond to the width of a standard door frame. Over the door frame, units C may be employed, the lower flanges 10a of which are tied to the header of the door frame in the same manner that the jambs of the door frame are tied to the adjacent flanges 10a of the adjacent units A.

Whenever it is desired to mount a window frame in the wall structure, such as the window

frame 29, shown in Fig. 7, and also in Figs. 1 and 2, this is readily accomplished by interposing a plurality of the units B between the lower portions of a pair of units A, and by interposing a plurality of the units C between the upper portions of the same units A. If metal window frames, such as the frame 29 are employed, having frame structures of Z-bar construction, these frames may be directly secured to the flanges 10a of the units A by bolts 30 and the sills and headers of the frames may be similarly secured respectively to the upper flanges 10a of the units B, and the lower flanges 10a of the units C. The width of the units A, B and C is such that the width of a plurality of these units corresponds to the width of standard window frames.

In erecting a floor skeleton for the building, if the span is greater than the length of the units A, preferably an I-beam 31 is supported at both ends in the foundation wall 13, intermediate two sides of this wall. Units A laid horizontally and assembled together in the same manner as in the building wall are then run across between one of the foundation walls and the I-beam 31, so that the flanges 10a at the ends of the units A rest on the foundation wall 13, and the I-beam 31. Thereupon other units D of the proper length are run across between the I-beam 31 and the opposite foundation wall 13 in alignment with the floor units A already laid.

When a two story building structure is desired, units A forming the skeleton walls of the upper story may be connected to units A forming the skeleton wall of the lower story as shown in Fig. 8 by means of T-irons 32 which have openings formed in the flanges thereof to receive the eye bolts 15. Horizontal channels 33 are then formed between the upper and lower units A and the adjacent flanges 10a of the upper and lower units are secured to the T-irons by means of the eye bolts 15 which lie within this channel 33. Horizontal reinforcing rods 34 are preferably disposed within the channel 33 and received within the eyes of the eye bolts 15 there located. A skeleton second floor formed from the units A and D may then be supported on the inwardly projecting flanges of the T-irons 32 and if desired paper-backed metal lath 35 for a ceiling can be suspended below the second floor from the units A and D in the same manner that the paper-backed metal lath 21 for the side walls is secured thereto. In the case of the second floor, however, the eye bolts 15 to which the ceiling lath 35 is secured, preferably run through the inner flanges of the T-irons 32.

Preparatory to erecting the roof skeleton for the building, gable units, such as the gable units E, F, G, H and I are first erected at the end walls of the building structure, these units being secured to the underlying units A or C, as the case may be, by overlapping the lower flanges 10a of the gable units with the upper flanges 10a of the underlying units A and C and interconnecting such flanges by the eye bolts 15 through which reinforcing rods 20 pass in exactly the same manner as adjacent units A are interconnected. Thereupon units A as best shown in Figs. 2 and 8, or other corresponding units of the proper length are laid diagonally from the tops of the side wall skeletons across to an I-beam 36 laid across the peaks of the two skeleton end walls. In order to tie the lower ends of the roof units A to the side walls, as well as to support a ceiling paper-backed metal lath 37 in place, angle irons 38 may be

bolted to the upper flanges 10a of the upper side wall units A.

To tie the roof units A to the angle irons 38 eye bolts 39 are employed, the eyes of which project downwardly from the channels between adjacent units A of the roof construction and which are secured to the upwardly extending flanges of the angle irons 38 by means of bolts 40. To enclose the space between the upper edges of the angle irons 38 and the lower ends of the roof units A, paper-backed metal lath 41 is employed which may be wired or otherwise secured to the upper flanges of the angle irons 38 and also wired or otherwise secured to the lower flanges 10a of the roof units A. The paper-backed metal lath 37 for forming a ceiling immediately underlying the roof may be secured to channels 18 and these channels in turn may be supported by bolts 42 from the inner flanges 20 of the angle irons 38.

It will be seen that the entire skeleton structure for the building may be erected without employing bracing, forms or scaffolding which must be later wrecked. It will also be seen that the various units when assembled as described are tied together so as to form a steel interconnecting structure wherein the various walls, floor ceiling, and roof are all tied together.

After the skeleton structure has thus been erected, the entire building structure can be quickly completed by applying pneumatic concrete to the external and internal faces of the structure to produce a monolithic building. The exterior coating which is designated 43 is applied by spraying the concrete from a concrete gun as before described to fill the channels 14 and 33 and to fill the spaces between the main bodies of the expanded reenforcements 12 and the sheets 11. As the pneumatic concrete is first applied by spraying against one of the units A, for example, it works through the expanded reenforcement 12 against the sheet 11 and thereupon the concrete is built up at the exterior of the reenforcement 12 to produce an exterior coating of concrete 43 for the unit and for the wall of the desired thickness. Naturally, the reinforcing rods 20 and 34 are embedded in the concrete and by reason of the filling of the channels 14 and 33, concrete pillars or columns and concrete beams are formed in the wall which greatly strengthen the same. Corner columns are also formed as shown in Fig. 6 which embed the rods 20 at the corners as well as the reinforcement rods 23. The roof is given the same treatment as the walls of the building as are the various floors of the building. Pneumatic concrete can also be sprayed onto the paper-backed metal lath 21 to form internal walls 44 for the building, or if desired this lath may be plastered in a conventional manner. Ceilings 60 may be similarly formed. Preferably as the wall surfaces are formed, a screed is run over the same to smooth the walls. With a concrete gun the application of the concrete to the skeleton frame of the building can be quickly accomplished with a minimum of labor. An exceedingly strong building structure is produced at a minimum of labor cost.

By reason of the fact that all the concrete is applied to the skeleton frame of the building structure produced by my various units, after the skeleton frame is erected, the various units employed are of light construction and can be readily handled and erected and all concrete employed may be sprayed onto the units right on the job. This eliminates the necessity for the

transportation of heavy concrete precast units to the job or the manufacture of such precast concrete units at the building site. It also eliminates the difficulty of handling such heavy precast units and the dangers attendant thereto.

The various units of my construction are flexible enough so they can be assembled to produce practically any desired type of building construction.

It will be readily appreciated that in place of using the channels 18 at the inner sides of my various units wood strips could be substituted therefor to which wall board can be nailed, if it is desired to finish off the interior wall with wall board. Also, if desired, the spaces between the metal lath 21 and the sheets 11 can be filled with any suitable type of insulating material to further insulate the walls. The air spaces, however, between the inner and outer walls of themselves form very good insulation against heat transmission and as before stated, the sheets 11 can be insulation board to further increase the insulating efficiency of the building.

As used in the claims the word "wall" shall be taken to mean walls proper, roofs, floors, or the like.

It will, of course, be understood that various changes may be made in the form, details, proportions and arrangements of the various parts without departure from the scope of the present invention which, generally stated, consists in the matter shown and described and set forth in the appended claims.

What is claimed is:

1. A skeleton building unit comprising a metal frame, a backing sheet extending across said frame at one side thereof and a pan-shaped foraminous reenforcement secured at its edges to said frame and bridging said backing sheet and frame at the same side of said frame as said backing sheet.

2. A skeleton building unit comprising a metal frame, a backing sheet extending across said frame at one side thereof and a pan-shaped foraminous reenforcement secured at its edges to said frame and bridging said backing sheet, and frame at the same side of said frame as said backing sheet, said frame having lateral attachment flanges at its side opposite said backing sheet.

3. A skeleton building unit to which concrete may be applied comprising a rectangular frame, a pan-shaped foraminous concrete holding reenforcement member attached at its edges to said frame and having a frame bridging portion spaced from one side of said frame and a backing sheet extending across the frame in spaced relation from said frame bridging portion of said member but at the same side of said frame as said frame bridging portion.

4. A skeleton building unit comprising a rectangular frame of angle iron construction having lateral attachment flanges lying in the same plane and main flanges lying in planes normal to the plane of said attachment flanges, a pan-shaped foraminous reenforcement the edges of which overlap and are secured to main flanges of said frame and a backing sheet extending across the frame and interposed between said main flanges and the pan-shaped reenforcement and forming a base against which concrete can be applied to be held by the reenforcement.

5. A skeleton building construction comprising, a plurality of building units each including a metal frame having an outer side and an inner

side, a backing sheet extending across said frame at the outer side thereof, a pan-shaped foraminous reenforcement secured at its edges to said frame to bridge said backing sheet at the outer side of said frame and outwardly from said backing sheet and attachment flanges projecting at the edges of said frame, said units being located in side-by-side relation with the adjacent attachment flanges of adjacent units overlapped, and means securing together the overlapped attachment flanges.

6. The structure defined in claim 5, and paper backed metal lath attached to said units at the sides thereof opposite said foraminous reenforcement.

7. A skeleton building wall to which concrete can be applied comprising, a plurality of skeleton building units, each unit including a metal frame having an outer side and an inner side, a backing sheet extending across the outer side of the frame, a pan-shaped foraminous reenforcement secured to the frame and bridging the backing sheet at the outer side of the frame, and connecting flanges at the inner side of said frame, said units being assembled in side-by-side relation with the connecting flanges of adjacent units being overlapped, eye bolts projecting through and interconnecting the overlapped flanges and reinforcing rods carried by the eyes of said eye bolts.

8. A skeleton building wall to which concrete can be applied comprising, a plurality of skeleton building units, each unit including a metal frame having an outer side and an inner side, a backing sheet extending across the outer side of the frame, a pan-shaped foraminous reenforcement secured to the frame and bridging the backing sheet at the outer side of the frame, connecting flanges at the inner side of said frame, said units being assembled in side-by-side relation with the connecting flanges of adjacent units being overlapped, bolts securing together the overlapped flanges of adjacent units, and bars secured at the inner sides of said units to said bolts and forming supports for an inner wall.

9. A skeleton building wall to which concrete can be applied comprising, a plurality of skeleton building units, each unit including a metal frame having an outer side and an inner side, a backing sheet extending across the outer side of the frame, a pan-shaped foraminous reenforcement secured to the frame and bridging the backing sheet at the outer side of the frame, connecting flanges at the inner side of said frame, said units being assembled in side-by-side relation with the connecting flanges of adjacent units being overlapped, securing members holding together the overlapped flanges of adjacent units, bars at the inner sides of said units attached to said securing members, and inner wall sheets located at the inner sides of said units and attached to said bars.

10. A skeleton building wall to which concrete can be applied comprising, a plurality of skeleton building units, each unit including a metal frame having an outer side and an inner side, a backing sheet extending across the outer side of the frame, a pan-shaped foraminous reenforcement secured to the frame and bridging the backing sheet at the outer side of the frame, connecting flanges at the inner side of said frame, said units being assembled in side-by-side relation with the connecting flanges of adjacent units being overlapped, securing members holding together the overlapped flanges of adjacent units,

bars at the inner sides of said units attached to said securing members, and paper-backed metal lath attached to said bars.

11. A skeleton building construction to which concrete can be applied comprising, a plurality of skeleton building units, each unit including a metal frame having an outer side and an inner side, a backing sheet extending across the outer side of the frame, a pan-shaped foraminous reinforcement secured to the frame and bridging the backing sheet at the outer side of the frame and connecting flanges at the inner side of said frame, certain of said units being assembled in side-by-side relation with the connecting flanges of adjacent units being overlapped to form channels between adjacent units, eye bolts projecting through and interconnecting the overlapped flanges of adjacent units and having eyes disposed within said channels and reinforcing rods disposed within said channels and carried by the eyes of said eye bolts.

12. A building construction comprising, a plurality of skeleton building units each unit including a metal frame having an outer side and an inner side, a backing sheet extending across the outside of the frame, a pan-shaped foraminous reinforcement secured to the frame and

bridging the backing sheet at the outer side of the frame and connecting flanges at the inner side of said frame, certain of said units being assembled in side-by-side relation with the connecting flanges of adjacent units being overlapped, securing members holding together the overlapped flanges of adjacent units, and a monolithic coating of concrete applied to the exterior of said units, filling the spaces between adjacent units, filling the spaces between said backing sheets and said foraminous reinforcements, embedding said foraminous reinforcements and extending outwardly therefrom.

13. The structure defined in claim 12, said securing members being eye bolts and the spaces between adjacent units forming channels within which the eyes of the eye bolts are received, reinforcing rods disposed within said channels and received by the eyes of said eye bolts and said concrete embedding the eyes of said eye bolts and said reinforcing rods therein and filling said channels.

14. The structure defined in claim 12, bars secured to said securing members at the inner sides of said units and an inner wall carried by said bars in spaced relation from said units.

RICHARD R. COLBURN.
